PUMP SERVOMOTOR WITH ROTARY CONTROL AND TORQUE MOTOR

Howard F. MacMillin and Ira B. Lawyer, Mount Gilead, Ohio, assignors to The Hydraulic Development Corp. Inc., Wilmington, Del., a corporation of Delaware

Application March 15, 1939, Serial No. 262,004

15 Claims. (Cl. 121—41)

This invention relates to hydraulic machinery, and in particular, to control devices for hydraulic pumps.

One object of this invention is to provide means for controlling the stroke and therefore the delivery of a reversible variable delivery pump including a pilot-valve member movable in a rotary direction within the servomotor piston to control the direction of motion of this piston.

Another object is to provide a servomotor of the type described above, wherein the pilot valve is rotated by a reversible torque motor, thereby providing a smooth rotary action without the jerking motion arising from the use of the solenoids commonly employed to actuate servomotor controls.

Another object is to provide a servomotor with a rotary pilot valve for controlling the direction of motion of the servomotor so that the servomotor is power-actuated in both directions of its motion rather than by power in one direction, and a compressed spring in the other direction.

Another object is to provide a pump flow-control shifting servomotor for a reversible variable delivery pump with a rotary pilot valve actuated by a reversible torque motor and a safety centering device for automatically shifting the pump flow-control member or shift ring to its neutral position, in response to a failure of power for actuating the pump.

Another object is to provide a hydraulic pump and press control circuit, including a rotary pilot valve responsive to the motion of the press platen to a predetermined position to actuate the pump servomotor so as to shift the pump flow-control member or shift ring to its neutral position, yet to put the pump slightly upon stroke again in the event that the platen tends to move away from this predetermined position.

Another object is to provide a hydraulic pump and press control circuit, as set forth in the preceding paragraph, wherein a safety centering device is associated with the pump flow-control member and servomotor for automatically moving the pump flow-control member to its neutral position in response to the failure of power for actuating the pump.

In the drawings:

Figure 1 is a diagrammatic view, partly in section, showing a hydraulic press and circuit including a variable delivery pump having the rotary controlled servomotor of this invention for shifting the pump flow-control member, together with a safety centering device for placing

the pump flow-control member in its neutral position in response to a failure of power for operating the pump.

Figure 2 is a central vertical section through the servomotor and its rotary pilot valve, according to this invention.

Figure 3 is a fragmentary view of the central portion of Figure 2, with the rotary pilot valve shifted in one direction.

Figure 4 is a view similar to Figure 3, but with the rotary pilot valve shifted in the opposite direction.

Figure 5 is a cross section taken along the line 5—5 in Figure 2.

Figure 6 is a cross section taken along the line 6—6 in Figure 2.

Figure 7 is a left-hand end elevation of the pilot valve operating linkage, looking in the direction of the line 7—7 in Figure 1.

Figure 8 is an enlarged longitudinal section through the tonnage control valve for regulating the pressing force of the press.

Figure 9 is a wiring diagram showing the circuit control motor 104 and switch 150.

GENERAL ARRANGEMENT

In general, the variable delivery pump control arrangement of this invention consists of a reversible variable delivery pump having a flow-control member and a servomotor piston connected to this flow-control member. Within a bore in the servomotor piston is located a sleeve with ports and a rotary pilot valve member having a rotary valve head with oblique ends cooperating with these ports. The rotary valve member is connected to a reversible torque electric motor, the shaft of which is also connected to a linkage leading to a rock arm. The latter is engaged by the control rod of a hydraulic press so as to be rocked when the press platen reaches a collar on the control rod and lifts the control rod.

The flow-control member of the variable delivery pump is also provided with an enlargement engaged on opposite sides by sliding collars which are urged against this enlargement by springs. In the event that a failure of power for the pump occurs, one of these springs will force the pump flow-control member to its neutral position, thereby acting as a safety arrangement. The weight of the press platen and plunger is therefore prevented from compressing the fluid beneath the plunger and operating the pump in a reverse direction as a motor, thereby eliminating the danger of rapid coasting down of the press

platens in the event of such a power failure. The auxiliary pump for supplying pressure fluid to the servomotor is preferably driven from the same shaft as the variable delivery pump so that the slight rotation given it by this compressed fluid, in the event of a power failure, immediately rotates it in the reverse direction and prevents any pressure from being trapped in the servomotor, thereby enabling the centering springs to perform their action of shifting the pump flow-control member to its neutral position.

Hitherto, where a spring has been used to actuate the servomotor in one direction, it has been found necessary to apply a force to actuate the servomotor in the other direction sufficient to compress the spring and thus store up the required energy. Where such a spring has been used it has also been necessary to make the spring force considerably greater than the required force in order to insure operation under all conditions, thus wasting power in overcoming this excess force. Hitherto, also, where reciprocating pilot valve members have been employed in association with servomotors for shifting pump flow-control members, it has been necessary to fit such valve members closely within their cylinders. As oil of rather high viscosity is necessarily used in such servomotors, it has been found difficult to push the pilot valve member in an endwise direction without the employment of considerable force.

In the present invention, however, the use of a rotary pilot valve member enables the servomotor spring to be eliminated since the servomotor is shifted in both directions by pressure fluid under the control of the rotary pilot valve member. Much less force is required to operate the pilot valve member since it has been found to be much easier to rotate the pilot valve member than to reciprocate it in an endwise direction, as in prior servomotors. This reduction of the force necessary to shift the pump flow-control member has also resulted in a greater ease of operation of the safety centering springs which are provided to shift the pump flow-control member to its neutral position, in the event of a power failure of the motor operating the pump. The rotary pilot valve member of the invention is also easily rotated by the linkage with which it is connected to the press control rod in such a manner as to shift the pump flow-control rod to put the pump on just sufficient stroke to take care of leakage and maintain the press platen in its retracted position. The reversible electric torque motor is also suitable for continuous stalled service as it is of a high torque, low amperage type. The pilot valve, however, can be rotated independently of the torque motor, either manually or by the press platen, since the press control rod is ordinarily provided with a manually operated lever for such manual control.

Hydraulic circuit

Referring to the drawings in detail, Figure 1 shows a hydraulic press circuit containing a variable delivery pump 1, arranged to supply pressure fluid to operate a press 2 having a surge tank 3, within which is a main cylinder release and by-pass valve 4. The latter causes the pressure in the main cylinder of the press to be released at the instant of reversal of the pump 1, while causing the discharge of the latter to be temporarily by-passed through this valve 4 into the surge tank 3. The details of this main cylinder

release and by-pass valve form no part of the present invention, and are disclosed in the Hubbert Patent No. 2,061,658, issued November 24, 1936.

5 A surge valve 5 in the top of the main cylinder of the press 2 serves to admit fluid to the upper part thereof to facilitate the gravitational descent of the main plunger until the platen of the press encounters resistance. The details of the surge valve 5 likewise form no part of the present invention, and are disclosed in the Ernst Patent No. 1,892,568, issued December 27, 1932. The surge valve 5, as disclosed in the above-mentioned patent, is adapted to be forcibly opened upon the return stroke of the press so as to release fluid from the upper part of the main cylinder directly into the surge tank 3.

The circuit shown in Figure 1 likewise contains a pilot pump 6 for supplying pressure fluid to the servomotor of the variable delivery pump 1, and preferably driven from the same shaft. The details of the pilot pump 6 and its driving connection with the variable delivery pump 1 form no part of the present invention, and are disclosed in the copending application of Walter Ernst, Ser. No. 41,281, filed September 19, 1935.

20 The circuit of Figure 1 also contains a relief valve 7, the details of which form no part of the present invention, and are disclosed in the Ernst Patent No. 2,086,295, issued July 6, 1937.

25 Within the surge tank 3 are pressure relief valves 8 and 9, connected on opposite sides of the main cylinder and by-pass 4. A check valve 10 is associated with the relief valve 9. The pressing force which the press exerts is controlled by a tonnage control valve 11, shown in longitudinal section in Figure 8.

30 The press 2 contains a double-acting main plunger 12 attached to a platen 13, which has an arm 14 extending laterally therefrom. Collars 15 and 16 are mounted upon a control rod 17, the collar 15 being engageable with the platen arm 14 when the platen 13 reaches its retracted position. The control rod 17 is guided in its reciprocation by brackets 18, one only being shown. The bracket 18 projects from the main cylinder 19 of the press 2. The main cylinder 19 contains a bore 20 for the reciprocation of the main plunger 12, and at its opposite end is provided with ports 21 and 22, connected respectively to the lines 23 and 24 leading to the forward and return pressure connections 25 and 26 of the variable delivery pump 1. A branch line 27 runs from the pipe 24 to the check valve 10, the pressure relief valve 9 and the main cylinder release and by-pass valve 4; likewise to the surge valve 5. From the main cylinder release and by-pass valve 4 the branch line 28 leads to the port 29 in the main cylinder 19, and to this branch line 28 is connected the pressure relief valve 8. The upper end of the main cylinder bore 20 also contains a port 30, from which the line 31 runs to the lower end of the tonnage control valve 11. From the latter the line 32 leads to the surge tank 3.

35 The pilot circuit, including the pilot pump 6 and the pilot pressure relief valve 7, includes the line 33 running from the surge tank 3 to the pilot pump 6. The line 34 leads from the relief valve 7 back to the surge tank 3, and the line 35 leads from the pressure connection of the pilot pump 6 to the casing 36 of the servomotor 37 of the variable delivery pump 1. The discharge or exhaust line 38 leads from the servomotor 37 back to the surge tank 3.

The reversible variable delivery pump 1 includes a pump casing 40 having a chamber 41 containing bearing pads 42, which slidably support and guide the pump shift ring or flow-control member 43. The latter is movable in opposite directions from its neutral position to alter the stroke of the pistons within the variable delivery pump, and thereby to alter or reverse the delivery of the reversible variable delivery pump 1, as is well known to those skilled in the art.

Servomotor construction

The casing 36 of the servomotor 31 (Figure 2) contains cylindrical bores 52, 53, 54 and 55 of decreasing diameters, together with annular recesses 56 and 57. At one end the casing 36 is flanged, as at 58, for attachment to the left-hand side of the variable delivery pump casing 40, and at its opposite end is flanged as at 59 to receive a head 60 bolted thereto. Within the servomotor casing 36 is a stepped servomotor piston 61 having two principal diameters 62 and 63, and continuing in the guide portion 64 which terminates in a piston rod 65, threaded as at 66 to screw into a pump flow-control member or shift ring 43 of the variable delivery pump 1. The guide portion 64 contains a keyway 67, within which is fastened a key 68, as by screws 69. A corresponding keyway 70 is provided in the bore 54. Piston rings 71, 72 and 73 reduce leakage past the pistons 62 and 63 and piston rod 65.

The servomotor piston 61 is bored to receive a pilot valve sleeve 74 containing ports 75, 76, 77, 78 and 79, and a uniform internal cylindrical bore 80. Running between the annular recess 56 and the drilled holes or ports 75 and 76 are drilled transverse holes or ports 81 and 82, passing through the piston 61. A longitudinal passageway 83 runs from the left-hand end of the piston head 62, through the body of the piston 61 and into a transverse hole or port 84. The piston 61 is likewise provided with transverse holes or ports 85 and 86, leading from the annular recess 57 to the sleeve holes or ports 78 and 79. A pipe connection 87 serves to receive the end of the pipe 35, supplying pressure fluid thereto from the auxiliary pump 6 to the annular recess 56. Similarly, a pipe connection 88 serves for receiving the end of the exhaust line 38 leading to the surge tank 3.

Mounted within the cylindrical bore 80 of the valve sleeve 74 and accurately fitted thereto, is a rotatable pilot valve head 89 having obliquely disposed ends 90 and 91. The oblique ends 90 and 91 are spaced apart a sufficient distance great enough to insure their covering the ports 75 and 77. The pilot valve head 89 is connected to or integral with a pilot valve stem 92, which continues in an enlarged portion 93 accurately fitted within the bore 94 in the casing head 60. Beyond the enlarged portion 93 is a further enlarged portion 95 fitting into correspondingly shaped annular groove 96 in the casing head 60 so as to restrain the pilot valve head 89 from endwise motion. A drainage passageway 97, connected to an exhaust line 98, carries away such fluid as may leak past the enlarged portion 93 of the valve stem 92.

The enlarged portion 95 is restrained from movement in one direction by the nut 99, which is bored to receive a packing 100, and threaded to receive a gland 101 about the hollow portion 102 of the valve stem 92. The portion 102 is

bored to receive the motor shaft 103 of the torque electric motor 104, and keyed thereto. The portion 102 is squared, as at 105, to receive a circular disc 106 mounted thereon. The disc 106 is cut away in an arcuate path, as at 107 (Figure 6), to limit the rotary motion of the valve head 89. This motion is limited by the stop pin 108, which is screwed into the head 60. The torque motor 104 is secured to the head 60 and flange 59 of the casing 36 by the cap screws 109.

The torque motor shaft 103 is provided with an extension 110 at the opposite end, and on this extension is mounted the arm 111. The arm 111 (Figures 1 and 7) carries a pin 112 which engages a slot 113 in the arm 114 of the bent lever 115. The latter is pivotally mounted, as at 116, and its opposite arm 117 is pivotally connected, as at 118, to the link 119, which in turn, is pivotally connected as at 120 to the rocker arm 121. The latter is pivotally mounted, as at 122, and at its opposite end is provided with a bifurcated portion 123 with rounded ends, engaged by the collar 16 on the press control rod 17.

Safety centering device

Threaded into the opposite side of the pump shift ring or flow-control member 43 from the connection 66 of the piston rod 65, is a centering rod 124 having thereon an enlargement 125, beyond which is an extension 126. Slidably mounted on opposite sides of the enlargement 125 are collars 127 and 128, engaging an internal flange 129 on the centering spring casing 130, which is secured to the pump casing 40 on the opposite side thereof from the servomotor casing 36. Secured to the spring casing 130 is an end casing 131, having a port 132 therein, normally closed by a plug and permitting checking the contents of the casing 131. The casings 130 and 131 contain coil springs 133 and 134, urging the collars 127 and 128 against either the centering rod enlargement 125 or against the internal flange 129 surrounding the latter.

Tonnage control valve construction

The tonnage control valve 11 (Figure 8) consists of a block 136 containing a longitudinal bore 137, reciprocably receiving a plunger 138, the upper end of which carries a head 139 urged downwardly by the coil spring 140. The upper end of the latter is engaged by the end enlargement 141 of the threaded shaft 142, which is threaded into the bore 143 in the block 116. A hand wheel 144 serves to adjust the position of the threaded shaft 142, thereby varying the force exerted by the coil spring 140 upon the plunger 138. The latter carries an annular portion 145, reciprocating in the guide bore 146, leakage being prevented by the washer 147, the packing 148 and the gland 149. A limit switch 150 is positioned with its switch arm 151 adapted to be engaged and shifted by the head 139 as it moves upwardly when the plunger 138 is shifted by a predetermined pressure exerted against its lower end 152 by pressure fluid supplied thereto from the line 31, leading to the main cylinder bore 20 above the pressing plunger 12. The limit switch 150 is normally closed, and thus permits the electrical control devices of the press 2 to remain energized until the plunger 138 of the tonnage control valve 11 overcomes the thrust of the coil spring 140 and rises and opens the switch 150.

Electric circuit

Referring to Figure 9, L₁, L₂, L₃, represent power lines. The pressure switch 150 with switch arm 151 is normally closed. In the circuit there is a push button switch 153. The reversing switch we have designated as 157. This has switch blades 158 to 163 inclusive. We have shown two solenoids as 155 and 156 for holding the push button switch 153 closed, and for holding the reversing switch 157 in one extreme position.

It will be noted that when the push button switch 153 which is normally held open by spring 154 is closed by the operator the circuit is completed through solenoid 155 and 156. The energizing of solenoid 155 holds the push button switch closed after the operator has removed his finger. The energizing of solenoid 156 closes the switch blades 158, 159 and 160 as shown in the sketch. This closes the circuit to the torque motor, running it in the direction corresponding to a servomotor movement to put the pump on stroke in the proper direction to close the press on the work.

When pressure builds up in the circuit sufficient to move the plunger 138 (Figure 8) against the action of springs 149 to trip the limit switch 150 this opens the circuit to the two solenoids, allowing the push button to return to its open position and allowing the reversing switch 157 to be actuated by the spring 164, closing switch blades 161 to 163 inclusive and opening blades 158 to 160 inclusive. This reverses the direction of rotation of the torque motor producing the reverse movement of the servomotor pilot valve, and shifting the stroke of the pump to deliver pressure fluid to the press in the proper direction to cause the press to open.

When the press platen approaches its open position the arm 14 contacting the collar 15 and operating through the rod 17, the linkage turns the torque motor shaft 110 against its normal direction of rotation and brings the servomotor back to neutral position. The torque motor remains energized during the time that it is held either stationary by the pin 168 in the slot 167, or when it is being forcibly reversed by the linkage.

OPERATION

In the operation of the hydraulic circuit the variable delivery pump 1 and auxiliary pump 6 are started in operation by the driving motor which drives both of them in common. Let it be assumed that the valve head 89 occupies its extreme right-hand position, shown in Figure 2, and that the auxiliary pump 6 is discharging pressure fluid through the line 35, into the port 87 and recess 58. Let it also be assumed that the bore 52 is full of fluid. If now the valve head 89 is rotated in either direction, it will uncover a portion of the port 77 and permit oil to be exhausted from the chamber 52, through the longitudinal passageway 83 and the ports 84, 77, 78, 85 and 88, to the exhaust line 38. The pressure of the fluid in the recess 58 will then cause the servomotor piston 61 to move to the left, likewise shifting the pump flow-control member 43 to the left and placing the variable delivery pump 1 upon stroke.

If the pilot valve head 89 is rotated only a small part of a revolution, the servomotor piston 61 will come to rest as soon as the sleeve 74 and its port 77 have moved sufficiently far to the left to become again covered by the pilot valve head 75

89. If, however, the latter is rotated about one-third of a revolution, the servomotor piston 61 will move to the left until its portion 62 strikes the head 60, without having fully covered the exhaust port 77. As previously stated, the stop pin 108 limits the rotation of the valve head 89 to the desired amount in either direction.

If it is desired to reverse the pump by shifting the pump flow-control member 43 in the opposite direction, the pilot piston head 89 is rotated in the reverse direction so as to cover the port 77 and uncover the port 75. When this occurs pressure fluid is admitted from the line 35, through the recess 56 and the ports 81 and 75, to the chamber or bore 52. As the exhaust port 77 is covered in this position of the valve head 89, the pressure in the chamber 52 will move the servomotor piston 61 to the right until the port 75 is covered, or until the servomotor piston 61 reaches the limit of its stroke. The rotation of the valve head 89 is accomplished, as previously stated, by the high torque low amperage electric motor 104, which is suitable for continuous stalled service and also is reversible for operation under power in both directions. The torque motor 104 is connected to the same electrical circuit as the tonnage control 11 so as to be responsive to reverse the variable delivery pump 1 in response to the operation of the tonnage control valve 11 when the pressing force reaches a predetermined maximum.

Thus, the rotation of the valve head 89 in one direction causes pressure fluid to be admitted through the line 23 and port 21, to the space 35 above the main plunger head 12 in the hydraulic press 2. The rotation of the pilot valve head 89 in the opposite direction, however, reverses the pump 1 and causes the pressure fluid to be discharged through the line 24 and port 22, into the space beneath the main plunger head 12. When the main pressing plunger is reversed in response to the control exerted by the tonnage control valve 11, the platen 13 moves upward until its arm 14 lifts the collar 15 and control rod 17 and rocks the rocker arm 120. The actuation of the latter then serves to rotate the torque motor shaft 110, through the linkage previously described, until the valve head 89 is rotated into a position where it halts the servomotor piston 61 at the point where the pump flow-control member 43 is in its neutral position. This position is just slightly away from the neutral position so as to compensate for the leakage past the main plunger head 12. By this arrangement, the pilot valve head 89 is automatically rotated until the platen 13 reaches its retracted position. This retracted position can be varied by moving the collar 16 up or down the press control rod 11.

From an examination of Figure 2 it will be seen that the diameter of the valve stem 92 at 93 is the same as the diameter of the pilot valve head 89, hence, the pilot valve is balanced hydraulically in a longitudinal direction. The port 76 is never uncovered by the pilot valve head 89, but being opposite the port 75, it serves for balancing the valve head 89 in a transverse direction. In order to obtain a perfect balance thereof, the stem 92 may be made the same diameter as the valve head 89 so that the face 91 is replaced by a diagonal slot in the valve head 89, the latter extending to the left as far as the end of the sleeve 74 when the parts are in the positions shown in Figure 2.

In the event of a failure of power for driving

the pumps 1 and 6, the main plunger head 12, by reason of the weight of itself and the platen 13, will tend to compress the fluid beneath the main plunger head 12. This pressure fluid will back up in the line 24 and will tend to cause the variable delivery pump 1 to operate as a motor, thereby accelerating the descent of the platen 13. When this occurs, however, the auxiliary pump 6, which is driven from the same shaft as the variable delivery pump 1, immediately also rotates in a reverse direction so that it sucks fluid out of the servomotor casing recess 56 (Figure 2). One of the springs 133 or 134 (Figure 1) will then be free to shift the centering rod 124 and the pump flow-control member 43 to its neutral position, halting the rotation of the pump 1 as a motor, and immediately halting the downward travel of the platen 13. This feature gives a safety control in the event of a power failure or breakdown of the pump operating motor.

It will be understood that we desire to comprehend within our invention such modifications as come within the scope of the claims and the invention.

Having thus fully described our invention, what we claim as new and desire to secure by Letters Patent, is:

1. In a servomotor control mechanism, a casing having fluid inlet and outlet openings, a fluid operable piston reciprocably mounted in said casing and having a bore with ports therein adapted to cooperate with said openings, and a rotatable valve member arranged in said bore adjacent said ports and having a valve head with a pair of oblique transverse end surfaces thereon for controlling said ports.
2. In a servomotor control mechanism, a casing having an inlet and an outlet opening adapted respectively to receive and discharge pressure fluid, a piston having a bore with ports therein adapted selectively to communicate with said inlet or said outlet opening, and a rotatable valve member in said bore adjacent said ports for controlling the latter, said valve member having a valve head with an oblique end surface thereon.
3. In a servomotor control mechanism, a casing having an inlet and an outlet opening adapted respectively to receive and discharge pressure fluid, a piston having a bore with ports therein adapted selectively to communicate with said inlet or said outlet opening, and a rotatable valve member in said bore adjacent said ports for controlling the latter, said valve member having a cylindrical valve head with spaced oblique end surfaces thereon.
4. In a servomotor control mechanism, a casing with fluid inlet and outlet openings, a piston having a bore with axially spaced radially arranged ports therein and a longitudinal passageway connecting one side of said piston with one of said ports, said ports being adapted respectively to communicate with said inlet and outlet openings and a rotatable valve member arranged in said bore adjacent said ports and having an obliquely disposed end surface thereon.
5. In a servomotor control mechanism, a casing having an inlet and an outlet opening adapted respectively to receive and discharge pressure fluid, a piston having a bore with ports therein adapted selectively to communicate with said inlet or said outlet opening and also including a longitudinal passageway connecting one side of said piston with one of said ports, and a rotatable valve member in said bore adjacent said ports for controlling the latter, said valve member
- 10 having a valve head with spaced oblique end surfaces.
6. In a servomotor control mechanism, a casing, a piston having a bore with axially spaced radially arranged ports therein and a longitudinal passageway connecting one side of said piston with one of said ports, and a rotatable valve member with oblique end faces in said bore adjacent said ports, said casing having a pressure fluid intake port arranged on that piston side which is remote from the piston side connected with said longitudinal bore, and also comprising an outlet bore for releasing fluid from the opposite piston side.
- 15 7. In a servomotor control mechanism, a piston having a bore with ports therein and also including a longitudinal passageway connecting one side of said piston with one of said ports, a rotatable valve member in said bore adjacent said ports for controlling the latter, and a casing for slidably receiving said piston, said casing having a pressure fluid intake opening arranged adjacent one piston side and adapted to communicate with one of said ports, and including a discharge opening adapted to communicate with another of said ports and arranged adjacent another piston side opposite said first-mentioned piston side, and said valve member having a valve head with spaced oblique end surfaces.
- 20 8. In a servomotor control mechanism, a casing with fluid inlet and outlet openings, a piston having a bore with axially spaced radially arranged ports therein and a longitudinal passageway connecting one side of said piston with one of said ports, said ports being adapted respectively to communicate with said inlet and outlet openings, a rotatable valve member in said bore adjacent said ports, and an electric torque motor adapted for continuously stalled service and having its shaft connected to said valve member, said valve member having a valve head with spaced oblique end surfaces.
- 25 9. In a servomotor control mechanism, a casing having a chamber and an inlet and outlet opening adapted respectively to receive and discharge pressure fluid, a piston reciprocably mounted in said casing and having a longitudinal bore with a transverse port adapted to connect said outlet opening with said chamber, and a rotatable valve member having a valve head with inclined end surfaces operable to open and close said port in response to the rotation of said valve member and also adapted selectively to establish communication between said inlet opening and said chamber.
- 30 10. In a servomotor control mechanism, a casing having a cylinder bore communicating with an inlet and outlet opening adapted respectively to receive and discharge pressure fluid, a fluid operable piston reciprocably mounted in said cylinder bore and having a longitudinal bore with transverse ports adapted to connect said longitudinal bore with said cylinder bore, and a rotatable valve member having a valve head with inclined end surfaces operable selectively to open and close at least one of said ports in response to the rotation of said valve member for selectively establishing or interrupting communication between said inlet and one of two oppositely acting piston sides, said piston having a longitudinal passageway connecting one side of said piston with one of said ports.
- 35 11. In a servomotor control mechanism, a casing having a chamber with inlet and outlet openings therein for respectively receiving and dis-

charging pressure fluid, a fluid operable piston reciprocably mounted in said chamber and having a longitudinal bore with transverse ports adapted to connect said bore with said chamber, a rotatable valve member having a valve head with inclined end surfaces operable to open and close said ports in response to the rotation of said valve member, and an electric motor adapted for continuously stalled service connected to said valve member.

12. In a servomotor control mechanism, a casing having a cylinder bore with inlet and outlet openings for respectively receiving and discharging pressure fluid, a fluid operable piston reciprocably mounted in said cylinder bore and having a longitudinal bore with transverse ports adapted to connect said longitudinal bore with said cylinder bore, a rotatable valve member having a valve head with inclined end surfaces operable selectively to open and close at least one of said ports in response to the rotation of said valve member, said piston having a longitudinal passageway connecting one side of said piston with one of said ports, and an electric motor adapted for continuously stalled service and arranged in alignment with and being connected to said valve member for rotating the latter.

13. In a fluid operated servomotor, a casing having a longitudinal bore with a fluid inlet and fluid outlet, a hollow piston reciprocably mounted in said bore and comprising axially spaced ports adapted respectively to communicate with said inlet and outlet for actuation of said piston, and a rotatable valve member with a skew head

mounted in said piston and cooperating with said ports to selectively cover and uncover at least one of said ports in response to the rotation of said head.

14. In a fluid operated servomotor, a casing having a longitudinal stepped bore with spaced fluid inlet and outlet openings therein, a reciprocable member slidably mounted in said bore and having axially spaced radially arranged ports therein adapted respectively to communicate with said inlet opening and said outlet opening to convey fluid pressure to said reciprocable member, and a valve member with a skew head rotatably mounted in said reciprocable member and cooperating with said ports to selectively cover and uncover at least one of said ports in response to the rotation of said head, said head having end surfaces disposed obliquely to the axis of rotation of said valve member.

15. In a fluid operated servomotor, a casing having a stepped bore with end chambers and spaced inlet and outlet openings disposed intermediate said end chambers, a hollow piston reciprocably mounted in said bore and comprising spaced radially arranged ports adapted respectively to communicate with said inlet and outlet openings, and also comprising a passageway adapted to effect communication between one of said end chambers and said outlet openings, and a valve member rotatably mounted in said piston and having a head with obliquely disposed ends for controlling said ports in response to the rotation of said head.
